UNITED STATES PATENT OFFICE.

KOSHIRO KANDA, OF SEATTLE, WASHINGTON.

DESIGN FOR A FOOT-WARMER.

49,742.

Specification for Design.

Patented Oct. 10, 1916.

Application filed June 12, 1916. Serial No. 103,333. Term of patent 3½ years.

To all whom it may concern:

Be it known that I, KOSHIRO KANDA, a citizen of Japan, and a resident of Seattle, in the county of King and State of Washington, have invented a new, original, and ornamental Design for a Foot-Warmer, of which the following is a specification, reference being had to the accompanying drawing, forming a part thereof.

In the drawings, the figure shown is a perspective view of my device.

I claim:

The ornamental design for a foot warmer as shown.

KOSHIRO KANDA.
